United States Patent Office.

EMANUEL ZORGER, OF GREENSBURG, INDIANA.

Letters Patent No. 60,815, dated January 1, 1867.

IMPROVED CAR COUPLING.

The Schedule referred to in these Letters Patent and making part of the same.

TO ALL WHOM IT MAY CONCERN:

Be it known that I, EMANUEL ZORGER, of Greensburg, Decatur county, Indiana, have invented a certain new and useful improvement in Railroad Car Couplings; and I do hereby declare the following to be a full, clear, and exact description thereof, reference being had to the accompanying drawings, making part of this specification.

My improvement relates to that class of devices by which cars are automatically coupled, and the first part of my invention consists in a peculiar shaped draw-head and catch, which act to receive and retain securely in position an ordinary connecting link. The second part of my invention relates to a method of locking the catch of my coupling, so that the link cannot be withdrawn by any unauthorized person; and the third part of my invention consists in certain devices for adjusting the draw-bar, so as to enable the coupling of cars whose draw-heads are at different heights above the track or road level. In the accompanying drawings,

Figure 1 is a vertical longitudinal section through a car-coupling embodying my improvement, the connecting link being shown as engaged with the gravitating catch.

Figure 2 is a section taken at the line $x x$, of fig. 1.

Figure 3 is a vertical longitudinal section of the draw-head, showing my gravitating catch elevated so as to enable the withdrawal of the connecting link.

Figure 4 is a horizontal longitudinal section of the draw-head at the line $z z$, of fig. 3; and

Figure 5 is a perspective view of my gravitating catch, on an enlarged scale.

My draw-head, A, is attached to a draw-bar, a' , and is provided with a customary flaring mouth, a , for the reception of the connecting link, S. The draw-head is composed of two distinct members, B and C, of which I term the part B the "upper jaw," and the other part, C, the "lower jaw;" said upper jaw having a double converging throat, bb' , while the jaw C has only one inwardly inclined face, e , whose apex is on a level with the bottom of the jaw, B, or nearly so. D is a gravitating catch, hung on a pivot, E, and adapted to vibrate within the vertical longitudinal slot, A', of the "upper jaw," B, and the arm, F, of said catch is slotted near its free end at f , for a purpose which will be hereafter described. The leg, G, of my gravitating catch, being that part of the device which sustains the strain of the connecting link, is made heavier and much stronger than the arm, E, and the back part of this member is provided near its lower end with a concavity, H, which serves to hold the connecting link in a proper position, whilst the front portion of said leg, G, has two chamfered faces, $g g'$, which enter a "V" shaped pocket, I, of the lower jaw, C, and bear against the shoulder, i . The shoulder, i , is located a somewhat greater distance from the mouth of the draw-head than the pivot, E, so that the strain will have a tendency to force the "upper jaw," B, and the lower jaw, C, asunder before the gravitating catch will be pulled out from its bearing in the pocket, I. This arrangement of the shoulder, i , with reference to the position of the pivot, E, enables the gravitating catch to act on the principle of an arch, so that the greater the strain brought to bear upon said catch the more securely it is held in position, provided the abutments do not spring out of their true position, and the "V" shaped pocket, I, prevents any lateral displacement of the catch. Placed athwart the slot, A', is a bar, k , having attached to it a staple, K, which passes through the slot, f , of the arm, F, and when a padlock is connected to said staple the catch can not be elevated so as to disengage the link, S, without first unlocking the padlock. The catch can be operated by a rope, J, or, if preferred, a chain or rod may be substituted for the rope. In order to adjust the draw-head to cars of different heights, I provide the following device: the hanger, L, which supports the draw-bar, a' , is mortised to receive two metallic friction plates, $N N'$, and these plates are forced to bear against the sides of said draw-bar by means of suitable springs, which springs may be of India-rubber, as at O, of spring steel, as at P, or of any other suitable material. By this arrangement my draw-head can be elevated or depressed, as may be desired, and retained at any place until the cars are coupled, when the draw-bar will equalize and adapt itself to the proper position. The draw-bar, a' , is prevented from being depressed too low by the stop R. The operation of my draw-head is as follows:

When two cars are brought together, the connecting link, S, is directed in a proper course to engage with the gravitating catch, D, by means of the converging throat, a , and as soon as the link strikes said catch the latter is elevated and describes an arc of a circle, as shown by the red arrow in fig. 1. The weight of the gravitating catch, and the manner in which it is hung, compels it to descend and rest against the shoulder, i , the moment the link passes beyond the heel of said catch, and as soon as the train is started the strain which is

thereby brought to bear upon the link, S, draws the end of the latter into the concavity, H, where it remains as long as there is any strain on said link. Whenever a train is to be run for a great distance without "switching off" or uncoupling any of the cars, the link can be secured in the draw-head so as to prevent its being displaced by simply attaching a padlock to the staple, K. This locking in of the link is not done to prevent its being displaced by the motion of the train, as the weight of the gravitating catch is sufficient to cause its retention, but it is done simply to prevent the cars from being uncoupled when not in motion, as when stopping at a station, or for the purpose of receiving fuel, water, &c., it being a very frequent occurrence for malicious persons to withdraw the ordinary coupling pins on such occasions, thereby compelling the train, after having been started, to return and attach the car which had been uncoupled. When it is desired to disconnect one car from the train, the brakeman or conductor has only to pull the rope, J, and the uncoupling is at once effected.

Among the many advantages which my coupling possesses over those now in use the following may be enumerated: First. Its reliability and safety, as the cars couple themselves the moment they are brought in contact with one another, and no amount of undulatory or lateral motion can disconnect them or injure the operative parts, besides which the cars can be uncoupled without endangering the life or limb of the brakeman. The operative parts of my coupling being completely enclosed within the draw-head, there is no chance of their being injured by anything dropping on them, and not being exposed to the inclemencies of the weather, they are not liable to be frozen up in winter or to become clogged with dust in summer. Another great advantage which is peculiar to this coupling consists in the means of locking the catch, so as to prevent the link from being withdrawn and stolen, which is a source of great annoyance and expense to railroad companies, and is frequently the cause of fatal accidents.

My coupling is no more expensive than the ordinary kind, and if it should become injured, it requires no great skill to repair it.

I claim herein as new, and of my invention-

1. The hinged gravitating catch D, when constructed with the concavity H, and chamfered faces g g', and with the slot f, and used in combination with a draw-head with converging throat and V-shaped pocket I, and also in combination with the hinged bar k, said parts being constructed substantially in the manner and employed for the purpose set forth.

2. In combination with the draw-bar a', and draw-head A, constructed and arranged to act automatically, substantially as set forth, I claim the friction plates N N', and tension springs O P, for holding the draw-head in any required position when coupling the cars, substantially as set forth.

In testimony of which invention I hereunto set my hand.

EMANUEL ZÖRGER.
